United States Patent

Des. 237,677
Patented Nov. 18, 1975

237,677

PLATE

Gerald Gulotta, New City, N.Y., assignor to Block
China Corporation, New York, N.Y.

Filed Dec. 20, 1973, Ser. No. 426,930

Term of patent 14 years

Int. Cl. D7—01

U.S. Cl. D7—23

FIG. 1

FIG. 2

FIG. 3

FIG. 4

FIG. 1 is a top plan view of a plate showing my new design;

FIG. 2 is a side elevational view thereof;

FIG. 3 is a bottom plan view thereof; and

FIG. 4 is a cross-section taken on the line 4-4 of FIG. 1.

I claim:

The ornamental design for a plate, substantially as shown.
